United States Patent Office.

AUSTIN B. CULVER, OF WESTFIELD, NEW YORK.

Letters Patent No. 96,086, dated October 26, 1869.

IMPROVEMENT IN TICKET-CLIPS.

The Schedule referred to in these Letters Patent and making part of the same.

To all whom it may concern:

Be it known that I, AUSTIN B. CULVER, of Westfield, in the county of Chautauqua, and State of New York, have invented a new and improved Ballot; and I do hereby declare that the following is a full, clear, and exact description, thereof, which will enable others skilled in the art to make and use the same, reference being had to the accompanying drawings forming part of this specification, in which—

Figure 1 represents a perspective view of my improved ballot.

Figure 2 is a transverse section of the same.

Similar letters of reference indicate corresponding parts.

The object of this invention is to protect and secure the purity of the elective franchise, by preventing fraudulent voting; and

The invention consists in providing a band around each ballot, in such manner that each ballot is kept separate, to prevent one voter from intentionally or accidentally putting in two or more votes, or, rather, to detect such double voting, in case it should be performed.

The ballot A, when handed to an inspector, or other officer of election, by a voter, is to be enclosed by the said official with a sheet-metal or other band, a, which will keep it separate, and prevent it from

becoming, in the urn, folded together with other ballots.

The sheet-metal band I prefer to make of lead, or other soft metal or material, which will readily bend without breaking.

The party receiving the ballots should have a number of such metal or other strips, and should fold one around each ballot received, and then put the same into the urn. Or the voter may be obliged to enclose each ballot in a band of the above construction for the same purpose.

The ballots are, by this means, kept entirely separated, so that fraudulent voters cannot put two or more ballots into the urn at once, without its being detected, and the superfluous votes rejected.

Having thus described my invention,

I claim as new, and desire to secure by Letters Patent—

The method above described of preventing fraudulent voting, namely, by enclosing the ticket of each elector, as soon as presented, with a clip of soft metal, substantially as specified.

AUSTIN B. CULVER.
